UNITED STATES PATENT OFFICE.

JESSEE CARTER, OF CAPTIVA, FLORIDA.

~~NOT EVIDENT COPY~~

ENVELOP.

No. 906,384.

Specification of Letters Patent.

Patented Dec. 8, 1908.

Application filed February 26, 1908. Serial No. 417,954.

To all whom it may concern:

Be it known that I, JESSEE CARTER, a citizen of the United States, residing at Captiva, in the county of Lee and State of Florida, have invented new and useful Improvements in Envelops, of which the following is a specification.

This invention relates to safety envelops, the object of the invention being to provide an envelop which, when sealed, will provide unusual strength in connection with the flaps and guard against the fraudulent opening of the envelop or rather revealing the fact that an attempt has been made to open the envelop to gain access to the contents thereof.

With the above general object in view, the invention consists in the novel construction, combination and arrangement of parts as will hereinafter be described, illustrated and claimed.

In the accompanying drawing:—Figure 1 is a plan view of the envelop before being folded, looking toward the inner face thereof. Fig. 2 is a plan view of the envelop partially folded or unsealed. Fig. 3 is a plan view of the envelop completely folded and sealed.

The envelop comprises a body or front portion 1 two oppositely located end flaps 2 and 3, a bottom flap 4 and a sealing flap 5.

The bottom flap 4 is provided with a projecting center tab 6 and loosely projecting end tabs 7 and 8. The end flaps 2 and 3 are provided with transverse slits 9 and 10 adapted when folded upon each other to receive the end tabs 7 and 8, and said end flaps are further provided with longitudinal slits 11 and 12 adapted when folded upon each other to receive a center tab 6. The sealing flap 5 is also provided with a slit 13 adapted when folded upon the end flaps 2 and 3 to receive the center tab 6.

One of the end flaps is gummed as shown at 14, the oblique edges of the bottom flap are also gummed on their inner side as shown at 15 and the sealing flap is gummed along

its oblique edges in the usual manner as indicated at 16.

The end flap 2 is first folded inward on the dotted folding lines shown in Fig. 1, after which the remaining end flap 3 is folded upon the other end flap and secured thereto by the gummed surface 14. The sealing flap 5 is then folded inward upon the end flaps, the gummed edge thereof being moistened so as to cause the flap 5 to adhere to the end flaps 2 and 3. The bottom flap is then moistened and folded inward upon the sealing flap 5 and the tabs 6, 7 and 8 which are gummed upon their outer faces as shown in Fig. 2 are moistened and inserted into and through the slits in the flaps 2, 3 and 5 and caused to adhere by pressure to the inner surfaces of the flaps, 2, 3 and 5. It will be found practically impossible to open such an envelop without giving visual notice of the fact that such an attempt has been made. This makes the envelop safe in transportation and adds materially to the strength of the connection between the various flaps of the envelop as a whole.

Having thus described the invention, what is claimed as new, is:—

A safety envelop comprising a body, end flaps provided with longitudinal and transverse slits, a sealing flap provided with a slit which registers with the longitudinal slits in the end flaps, and a bottom flap provided with a gummed center tab and gummed end tabs which project in opposite directions laterally away from the center tab, said center and end tabs being adapted when said bottom flap is folded to be inserted through the slits in the sealing flap and end flaps and to adhere to the inner surfaces of said flaps, substantially as described.

In testimony whereof I affix my signature in presence of two witnesses.

JESSEE CARTER.
